FINGER RING

George C. Minister, Columbus, Ohio

Application July 18, 1935, Serial No. 32,057

5 Claims. (Cl. 63—15)

This invention relates to an improved finger ring and method of producing the same, the object of the invention being to provide a finger ring of normal size and of a desired precious metal content, but which will be less expensive to manufacture and purchase than ordinary finger rings of comparable size and having corresponding alloy composition.

For a further understanding of the invention, reference is to be had to the following description and the accompanying drawing, wherein:

Fig. 1 is a perspective view of the upper or outer portion of the body strip employed in the construction of the finger ring comprising the present invention;

Fig. 2 is a similar view of the lower or inner portion of the body strip;

Fig. 3 is a vertical longitudinal sectional view taken through the body strip prior to bending and its accompanying lining strip;

Fig. 4 is a vertical transverse sectional view on the line IV—IV of Fig. 3;

Fig. 5 is a vertical transverse sectional view taken through the finger ring comprising the present invention in its final or complete form;

Fig. 6 is a detail longitudinal sectional view disclosing a modified form of the body strip comprising the present invention;

Fig. 7 is a view of a finger ring formed from the body strip disclosed in Fig. 6.

Referring more particularly to the drawing, in the manufacture of my improved finger ring, I employ a body member, indicated at 1, and a lining strip as indicated at 2. The body member is preferably in the form of a casting or stamping and, when initially produced, comprises a concave central section 3 joined at its sides with downwardly and outwardly inclined walls 4 which, in turn, terminate in substantially flat, outwardly extending finger extensions 5 of reduced transverse width as compared with the central section or region 3. The body member is preferably formed from a metallic alloy of high precious metal content, the use of such a high precious metal content being rendered possible in a ring which will be economical to purchase, by the features of formation hereinafter described.

In the formation of the body member 1, whether by casting or stamping, there is produced in the under or inner side thereof, as disclosed in Figs. 2, 3 and 4, a plurality of pockets or cavities 6 which are disposed between the adjoining surfaces of the central section 3 and the sloping side walls 4. Usually this portion of a finger ring is of solid design but by producing these pockets

or cavities, the exterior configuration of the ring remains exactly the same as in the conventional construction but I save the weight and cost of the metal which has been removed from the ring by the formation or presence of said pockets or cavities.

To prevent these pockets or cavities from being visible from the inner portions of the ring, I employ the lining strip 2 which comprises a flat strip of metal and when initially produced, corresponds exactly with the plan configuration of the body 1. The lining strip is placed on the inner side of the body 1 and is secured thereto by solder or other suitable means so that it becomes in effect a component or integral part of the ring assembly.

Following the soldering of the lining strip to the under side of the body member 1, the ring is then bent around a suitable form of standard construction provided for that purpose so that it will assume the conventional circular formation of the ordinary finger ring. I have discovered that during this bending operation, it is necessary to truss or reenforce the hollowed interior construction of the body member 1 to prevent its de-forming when bent to a circular form. Without such reinforcement, the body member in the region of the pockets or cavities 6 tends to collapse or to break or fracture so that the resulting construction of the ring is imperfect. I have avoided this condition, however, by the provision of the integral reinforcing ribs 7 which are formed with and constitute an integral part of the body member 1. These ribs strengthen the body member in the region of the pockets or cavities 6 so that when the body member is bent to circular form, the tendency of the same to collapse and produce an imperfect design is precluded.

In the form of my invention disclosed in Figs. 1 to 5, the ribs 7 are terminated along their lower sides in slightly spaced order from the adjacent surfaces of the lining strip 2 and are not soldered to said lining strip as are the other portions of the body member. This prevents the ribs, after being bent, from marring the smooth circular interior of the strip 2. It is possible, however, to solder the ribs 7 to the lining strip by the construction disclosed in Fig. 6, wherein the ribs are slightly notched as at 8 which facilitates their bending and assuming the desired arcuate configuration along their inner surfaces, the notches being closed by the bending of the ring, as disclosed in Fig. 7, and thus avoid placing any strain on or

imparting thrusts to the lining which would mar its configuration.

In the bending of the body member 1, the upper surface of the central section 3 assumes a substantially flat formation as disclosed at 9 in Fig. 5, adapting the ring for the reception of monograms, class or fraternity symbols, or other desired forms of embellishment. A ring constructed in accordance with the present invention 10 may be truthfully marked to designate the high precious metal content of the alloy from which it is formed, will have the size and form of a corresponding ring of conventional design and yet may be produced and sold at a considerably lower cost 15 than the conventional ring because of the presence of the pockets or cavities indicated at 6.

I am aware of the fact that rings have been made heretofore wherein the body member is formed from a precious metal alloy of high value 20 and the inner or lining member from an alloy of much lower value. In the present invention, however, all the metal in the ring may be of an alloy having a high precious metal content together with economy in manufacture and sales 25 costs.

What is claimed is:

1. A finger ring comprising a body member having a plurality of pockets or cavities provided in the central region thereof, reenforcing ribs 30 disposed in said pockets or cavities and integrally formed with said body member, and a lining strip secured to the inner or under side of said body member and concealing said pockets or cavities from external view.
- 35 2. A finger ring comprising a body member of precious metal, the central portion of said body member having the inner side thereof formed with a plurality of pockets which open to the inner side of said member, reenforcing ribs integrally formed with said body member and disposed in said pockets, and a lining strip of precious metal corresponding to that employed in said body member, said lining strip being secured to the inner side of said body member to conceal 40 said pockets from exterior view.
- 45 3. A finger ring blank comprising a body member formed to provide a centrally disposed de-

pressed region terminating in downwardly and outwardly inclined side walls and flat outwardly projecting finger extensions, the lower portion of the depressed central region lying substantially in the same plane as the lower surfaces of said finger 5 extensions, reenforcing ribs integrally formed with said body member and arranged to occupy pockets formed in said body member between said depressed central region and the downwardly and outwardly inclined side walls, and a flat 10 lining strip formed to be secured to the under side of said body member and possessing the plan configuration of the latter.

4. A finger ring blank comprising a body member formed to include a centrally disposed concave section, the opposite sides of said section terminating in downwardly and outwardly inclined side walls and a pair of substantially flat relatively narrow finger extensions, reenforcing ribs integrally formed with the concave central 15 section of said body member and the downwardly inclined side walls thereof, said ribs being disposed in said body member to span pockets formed between the concave central section 20 thereof and said side walls, and a flat lining strip 25 possessing the plan configuration of said body member and adapted to be soldered thereto, said lining strip having no direct connection with the adjoining surfaces of the reenforcing ribs.

5. A finger ring blank comprising a body member formed to include a centrally disposed concave section, the opposite sides of said section terminating in downwardly and outwardly inclined side walls and a pair of substantially flat relatively narrow finger extensions, reenforcing 30 ribs integrally formed with the concave central section of said body member and the downwardly inclined side walls thereof, said ribs being disposed in said body member to span pockets formed between the concave central section 35 thereof and said side walls, and a flat lining strip possessing the plan configuration of said body member and adapted to be soldered thereto, said ribs being notched to facilitate the bending of the 40 body member into circular form.

GEORGE C. MINISTER.
